(57) **CLAIM**

The ornamental design for a bib with pocket, as shown and described.

DESCRIPTION

FIG. 1 is a back perspective view of a bib with pocket in a configuration where the body of the bib is withdrawn from the pocket.

FIG. 2 is a front elevation view of the bib with pocket in the configuration where the body of the bib is withdrawn from the pocket.

FIG. 3 is a back elevation view of the bib with pocket in the configuration where the body of the bib is withdrawn from the pocket.

FIG. 4 is a right side elevation view of the bib with pocket in the configuration where the body of the bib is withdrawn from the pocket.

FIG. 5 is a left side elevation view of the bib with pocket in the configuration where the body of the bib is withdrawn from the pocket.

FIG. 6 is a top plan view of the bib with pocket in the configuration where the body of the bib is withdrawn from the pocket.

FIG. 7 is a bottom plan view of the bib with pocket in the configuration where the body of the bib is withdrawn from the pocket.

FIG. 8 is a perspective view of the bib with pocket in a configuration where the body of the bib is folded into the pocket. The surface of the pocket shown is the inside surface of the pocket illustrated in FIGS. 1-7.

FIG. 9 is a front elevation view of the bib with pocket in the configuration where the body of the bib is folded into the pocket.

FIG. 10 is a back elevation view of the bib with pocket in the configuration where the body of the bib is folded into the pocket.

FIG. 11 is a right side elevation view of the bib with pocket in the configuration where the body of the bib is folded into the pocket.

FIG. 12 is a left side elevation view of the bib with pocket in the configuration where the body of the bib is folded into the pocket.

FIG. 13 is a top plan view of the bib with pocket in the configuration where the body of the bib is folded into the pocket; and,

FIG. 14 is a bottom plan view of the bib with pocket in the configuration where the body of the bib is folded into the pocket.

The broken lines shown as dashed lines represent stitching seams of the bib with pocket which form no part of the claimed design.

(Continued)

The broken lines shown as dot-dashed lines represent portions of the bib with pocket that form no part of the claimed design. The claimed design extends to the dot-dashed line boundaries but does not include the boundaries or the area within the boundaries.

1 Claim, 12 Drawing Sheets
